ELECTRIC IRON SOLEPLATE

John L. Eaton, Jr., Delanco, N.J., and Roger V. Eeckhout,
Warminster, Pa., assignors to SCM Corporation, New
York, N.Y.

Filed Sept. 17, 1973, Ser. No. 398,113

Term of patent 14 years

Int. Cl. D7—05

U.S. Cl. D7—204

FIG. 1 is a perspective view of an electric iron soleplate showing our new design, the broken line illustration in this view only being for illustrative purposes to indicate environmental use; and

FIG. 2 is a bottom plan view of the electric iron soleplate shown in FIG. 1.

We claim:

The ornamental design for an electric iron soleplate, as shown and described.
